UNITED STATES PATENT OFFICE.

DIMITRI SENSAUD DE LAVAUD, OF SÃO PAULO, BRAZIL, ASSIGNOR TO FLOCKHART RING
CASTING CO., OF NEWARK, NEW JERSEY, A CORPORATION OF NEW JERSEY.

CENTRIFUGAL CASTING-MACHINE.

1,257,325.

Specification of Letters Patent. Patented Feb. 26, 1918.

Application filed March 9, 1917. Serial No. 153,658.

To all whom it may concern:

Be it known that I, DIMITRI SENSAUD DE LAVAUD, a citizen of the United States of Brazil, residing at São Paulo, Brazil, have 5 invented new and useful Improvements in Centrifugal Casting-Machines, of which the following is a specification.

My invention relates to centrifugal casting machines.

10 My invention has for its principal object to provide means for casting piston rings and other small articles, and especially those having non-concentric inner and outer peripheries, in quantities and at a rapid rate; 15 and consists in the combination, construction and arrangements of parts herein illustrated, described and claimed.

20 In the accompanying drawings, in which similar reference characters designate corresponding parts in all views, I have illustrated a machine particularly adapted for making piston rings as a preferred embodiment of my invention, and,

25 Figure 1 is an end view of a machine of the preferred form;

Fig. 2 is a horizontal section taken approximately on the line 2—2 of Fig. 1;

Fig. 3 is a partial vertical central section, 30 taken approximately on the lines 3—3 of Figs. 1 and 2;

Fig. 4 is a sectional detail taken approximately on the line 4—4 of Fig. 3;

Fig. 5 is an end view, and Fig. 6 a section on the line 6—6 of Fig. 5, respectively, of a 35 piston ring cast in the machine.

In the form of apparatus shown in the accompanying drawings, the machine comprises a bed plate 1 upon which are mounted the standards 2 carrying longitudinal rods 3 upon which sleeves 4 are slidably mounted. The sleeves 4 carry an axle 5 upon which is revolvably mounted a hub 6, and pinions 8, which are keyed to the axle, and are adapted to be revolved with the axle when the handle 7 is turned, this causing the pinions to travel upon the racks 9 of the longitudinal bars 3, causing the sleeves, axle, hub, and members carried thereby, to be horizontally moved in a direction parallel to the longitudinal bars 3.

The hub 6 is free to revolve upon the axle 5 and a pin 10 is provided upon one of the sleeves 4 adapted to engage suitable notches in the hub 6 to maintain the hub in the desired angular position. The hub 6 carries

a number of spokes 11, in the form shown the number being four. Upon each of the spokes 11 is mounted upon ball bearings 12 a collar or bushing 13 free to revolve about the spokes. The collar 13 forms the base of 60 a chuck to carry the molds, which chuck comprises in the form shown in addition to the collar a number of clamping members 14 which are preferably mounted upon the collar 13, fitting grooves in the outer surface thereof and held in position by pins 15 which allow of some movement of the members 14 toward and away from the axis of the collar. These clamping members project outwardly from the axle 5 and preferably have beveled ends 16 adapted to engage a friction clutch 17 by means of which the mold carrying chuck is revolved.

The means for revolving the chuck comprise a friction clutch 17 mounted upon ball 75 bearings 18 suitably supported upon one end of the base plate, for instance by means of the end plate 19. This clutch 17 may be revolved by any suitable source of power, as by means of a driven flexible cable 20.

80 The casting is done in molds 21 which are made of such a size and shape, preferably circular, that they may be placed within the clamping members 14 of the chuck to be revolved thereby while the casting operation is being performed. These molds 21 are adapted to form the side and outer surfaces of the casting while the inner surface is determined by the quantity of metal used, due to the fact that the casting 90 is done under centrifugal force, which inner surface is therefore circular in shape. In the form shown, each mold comprises a surface 22 for the outer periphery of the casting and a surface 23 against which one of the side surfaces of the casting is formed, while the other side surface of the casting is formed against the back of the next adjacent mold, a series of the molds being 95 placed in the chuck at one time as shown in the drawing. The friction clutch member 17 is provided with an extension 24 adapted to fit within the end of the chuck and bear against the series of molds, pressing these down against a spring 25 which seats 100 against the collar 13, and exerts upon the molds sufficient pressure to hold them in contact during the casting operation.

105 The metal may be introduced into the mold in molten state by means of the trough 110

26 fed from the funnel 27, which trough is rotatably supported upon a bracket 28 and extends through a central opening of the clutch 17 to the interior of the chuck member and through central openings of the molds extending the entire length of the series of molds. This trough is revolvably carried upon the bracket 28 and provided with a handle 29 by means of which it may 5 be rotated to discharge the molten metal 10 from the opening 30 into the molds.

Extending from the end plate 19 downward along the circumference of the circle through which the outer edges of the chucks 15 revolve there may be provided a plate 31 which will prevent the molds from being discharged from the chucks when the latter are rotated upon the axle 5, and at the end of this plate 31 is a receiving table 32 upon 20 which the molds containing the castings are deposited.

This apparatus is suitable for casting objects of various shapes under centrifugal force but is particularly adapted to the 25 casting of piston rings and other articles having substantially circular inner and outer peripheries, which peripheries need not be concentric. In Fig. 4 a mold 21 for a piston ring is shown on an enlarged scale, 30 illustrating how the surface 22 against which the outer periphery of the casting is to be made is formed eccentric to the axis about which the mold is to be revolved. In dotted lines is shown the outer molding surface 35 face of the next succeeding mold of the series, this being placed so as to bring the greater quantity of metal upon the opposite side of the axis in order to balance the operation of the machine.

40 The operation of the machine is as follows: The chuck which is projecting in an upward direction is filled with molds 21, these being arranged alternately as indicated in Fig. 4 to balance the operation; 45 the pin 10 is then released, and the chucks revolved upon the axle 5 to bring the uppermost chuck through an angle of 90° opposite to the friction clutch 17 in which position it is held by the pin 10. The handle 7 is then revolved, causing the beveled ends 50 16 of the clamping members of the chuck to be advanced into and engage the clutch 17. The clutch 17 being revolved by the cable 20 causes the revolution of the chuck upon 55 its bearing 12, and molten metal is poured into the funnel 27, filling the trough 26 from which it is dumped into the molds by rotation of the trough by means of the handle 29. The molds during the operation 60 are held firmly against one another by the springs 25 pressing them against the extension 24 of the clutch 17.

As soon as the metal has time to harden, 65 the handle 7 is revolved, causing the pinions 8 to travel upon the rack 9, and withdraw-

ing the chuck from contact with the clutch 17. The pin 10 is then released, and the chucks given a quarter turn about the axle 5, the uppermost chuck in the meanwhile having been filled with molds as before, 70 the result of this quarter turn being to bring the next chuck opposite the clutch 17, and the chuck in which the castings have just been formed over the table 32 upon which the castings and molds are deposited. This 75 table 32 may be removed in any suitable manner and the castings separated from the molds, which are ready to use over again.

Having now described my invention, I claim and desire to secure by Letters Patent: 80

1. A machine for casting by centrifugal force hollow articles having eccentric inner and outer surfaces, comprising a mold for the outer surface, and means for revolving said mold about an axis eccentric to its 85 molding surface.

2. A machine for casting hollow articles having eccentric circular inner and outer surfaces, comprising a mold for forming the outer surface and means for revolving said 90 mold about the axis equidistant from the desired inner surface.

3. A machine for casting under centrifugal force articles having eccentric inner and outer surfaces, comprising molds for forming the outer surfaces, and a revolvable chuck adapted to rotate said molds about an axis 95 eccentric to said molding surfaces.

4. A centrifugal casting machine comprising a series of molds, a revolvable chuck 100 adapted to receive and rotate said molds simultaneously, and a filling trough adapted to be introduced within and withdrawn from said molds.

5. In a centrifugal machine for casting 105 piston rings and like articles, molds for forming the outer surface and one end surface of a ring, and a chuck adapted to hold a series of said molds arranged so that the reverse side of a mold serves to form the 110 other end surface of the ring cast in the next adjacent mold.

6. In a centrifugal casting machine, the combination comprising means for rotating molds, a series of molds, and means for 115 bringing said molds successively into position to be rotated by said rotating means.

7. In a centrifugal casting machine, the combination comprising a friction clutch, a series of molds provided with friction surfaces adapted to be engaged by said clutch, and means for successively bringing said 120 molds into contact with said clutch.

8. In a centrifugal casting machine, the combination comprising a frame, a hub rotatably mounted thereon, a series of molds rotatably carried by said hub, means for rotating a mold, and means for operating the hub to bring the molds successively into position to be actuated by said rotating means. 125 130

9. In a centrifugal casting machine, the combination comprising a frame, a hub rotatably mounted thereon, a series of chucks rotatably carried by said hub, molds adapted to be carried and revolved by said chucks, a driven revoluble clutch, means for rotating said hub to bring said chucks successively opposite said clutch, and means for bringing said clutch and opposed chuck into operative relationship.
10. In a centrifugal casting machine, the combination comprising a frame, a hub reciprocally and rotatably mounted thereon, a series of chucks rotatably carried by said hub, molds adapted to be carried and revolved by said chucks, a driven revoluble clutch, means for rotating said hub to bring said chucks successively opposite said clutch, and means for reciprocating said hub to cause engagement and disengagement of the opposed chuck with the clutch.
11. In a centrifugal casting machine having molds, a chuck adapted to receive and rotate molds, comprising a collar having longitudinal peripheral grooves, clamping members fitting said grooves and pivotally attached to said collar, and extending longitudinally beyond the collar, said members having beveled ends, and a friction clutch adapted to engage said beveled ends and cause rotation of the chuck.
12. In a centrifugal casting machine, the combination comprising a frame, a hub rotatably mounted thereon, a series of chucks rotatably carried by said hub, molds adapted to be carried and revolved by said chucks, a driven revoluble clutch, means for rotating said hub to bring said chucks successively opposite said clutch, means for bringing said clutch and opposed chuck into operative relationship, and a table disposed to receive the molds and castings from one chuck as a following chuck is brought opposite the clutch.
13. A centrifugal casting machine comprising a series of molds, and a revoluble chuck adapted to hold said molds axially in line and to rotate them simultaneously about their axes.

In testimony whereof I have signed my name to this specification.

DIMITRI SENSAUD DE LAVAUD.
